CLAIM

The ornamental design for a backless bra, as shown and described.

DESCRIPTION

FIG. 1 is a front elevation view of a backless bra.

FIG. 2 is a right-side perspective view of the backless bra.

FIG. 3 is a right-side elevation view of the backless bra; the left side elevation view being an identical mirror image thereof.

FIG. 4 is a rear elevation view of the backless bra.

FIG. 5 is a top elevation view of the backless bra.

FIG. 6 is a bottom elevation view of the backless bra.

FIG. 7 is a front elevation view of FIG. 1 shown in a first alternate configuration;

FIG. 8 is a front elevation view of FIG. 1 shown in a second alternate configuration; and,

FIG. 9 is a front elevation view of FIG. 1 shown in a third alternate configuration.

In the drawings, the broken lines indicate portions of the article not claimed and form no part of the claimed design. The broken lines in the drawings shown within the cup panels and/or straps of the article represent unclaimed seams and form no part of the claimed design.

1 Claim, 9 Drawing Sheets
